UNITED STATES PATENT OFFICE.

JOHN MERRY, OF NEW YORK, N. Y., ASSIGNOR TO BIGELOW CARPET COMPANY, A CORPORATION OF MASSACHUSETTS.

DESIGN FOR CARPET.

42,693.

Specification for Design.

Patented July 2, 1912.

Application filed May 28, 1912. Serial No 700,333. Term of patent 3½ years.

To all whom it may concern:

Be it known that I, JOHN MERRY, a subject of the King of Great Britain, residing at New York city, in the county of New York and State of New York, have invented a new, original, and ornamental Design for a Carpet, of which the following is a specification, reference being had to the accompanying drawing, forming part thereof.

The drawing illustrates a portion of a carpet showing my new design.

I claim:

The ornamental design for a carpet, as shown.

JOHN MERRY.
